MAURICE HÉLIOT, OF TROYES, FRANCE

APPARATUS FOR TAILORING GARMENTS

Application filed November 19, 1928, Serial No. 320,518, and in France January 7, 1928.

This invention has for object a new apparatus adapted for tailoring undergarments or garments tailored with or without sleeves, apparatus which provides an important improvement in the method of proceeding and provides a definite progress over apparatus hitherto in use.

These latter consist, in fact, of wooden forms with articulated arms and give very poor results owing to their great thickness which does not leave a clearly defined crease in the article treated and owing to the bad conductivity of the wood, which prevents the article receiving the required amount of heat necessary for a perfect pressing; further the articulations tend to nip the material and cause the worker to rumple the article by lifting the arms when he removes said article.

The present invention remedies all these inconveniences by reason of the particular characteristics shown in the accompanying drawings given by way of example. Fig. 1 of these drawings shows the apparatus in elevation in the pressing position. Fig. 2 showing it in the fitting on or removal position. Fig. 3 shows it in plan.

The new apparatus or form comprises, in principle, a metal board B of dimensions corresponding to the size of the waistcoat to be pressed mounted at its base and at its middle portion on an axis C which freely pivots in a support G which is secured to a cross piece of any kind H. It is therefore possible without effort to give a rotation to the board B.

On the same cross piece H are fixed vertically two columns A and A' each at equal distance from the centre of the board B represented by the axis C. These columns are fixed at their bases by supports F and F' which are displaceable on the cross piece H; at their upper part these columns each support a series of arms D, E and D', E' which receive the arms of the waistcoat to be treated when the body thereof has been fitted on the board B.

The two arms D, E both form together an assembly mounted on a socket J which, held at suitable height by a collar, pivots horizontally having as axis, the column A. The

arm E secured on the socket J is integral therewith and its lower position will mark the lower fold of the arm of the waistcoat. The arm D is movable on an axis K which is integral with the socket J. It is actuated by a small lever which permits of exactly fixing the position; this movable arm D with its upper position marks the upper fold of the sleeve.

The two arms D', E' mounted on the socket J' and supported by the column A are symmetrical to the arms D, E and have exactly the same disposition.

The operation of the apparatus thus constructed is the following:

The board B having been placed parallel to the cross piece H, the arms D, E and D', E' being movable are slightly displaced from the plane of the form. The body of the waistcoat is fitted readily upon the board B whose outline has been prepared according to the cut of the waistcoat to be treated. It only remains to fit on the two sleeves respectively on the arms D, E and D', E' which are there for that purpose and the position of which will be that shown in Fig. 2 that is to say the movable arms D and D' covering respectively the arms E and E' which makes the putting on of the sleeve an easy operation in view of the fact that the distance apart of the arms is about three times larger in Fig. 1 than it is in Fig. 2. When the arms are fitted in position, the arms D, E and D', E' automatically take a position in the plane of the form and there only remains to put the arms D and D' in the position of Fig. 1.

Supposing that the cross piece H is mounted on a chariot the whole can be put into a chest heated to a high temperature and removed after a few minutes. The removing of the garment is the easiest possible operation; it is sufficient to return the arms D and D' to the position of Fig. 2, a half turn of the board B will remove the sleeves without any effort, pulling, deformation or creasing of the material; the body of the garment will be taken by its upper part and pulled vertically. The waistcoat will have been pressed without fatigue with contours clearly defined and the folding will then be very easy to do.

The columns A and A' being displaceable on the cross piece H the part B can be readily replaced or rendered extensible; it is possible to form any sizes with different lengths of sleeve by arms of appropriate length and extensible.

The whole apparatus can be constructed of hollow material for heating by steam, electrical resistances and other heating means.

10 Owing to the independence of the arms, garments such as waistcoats without sleeves or with short sleeves can be equally readily treated.

I claim:

15 1. Apparatus for tailoring and pressing garments comprising a frame, a pivot on which said frame is adapted to turn, vertical columns disposed symmetrically on each side of said frame and arms mounted on said col-

20 umns adapted to engage the sleeves of a garment.

25 2. Apparatus for tailoring and pressing garments comprising a frame, a vertical pivot on which said frame is adapted to turn, vertical

30 columns disposed symmetrically on each side of said frame but independent thereof and arms movable in relation to each other carried by said columns for engaging the sleeves of a garment.

35 3. Apparatus for tailoring and pressing garments comprising a pivotally mounted frame, columns mounted adjacent said frame and disposed symmetrically on each side thereof, an arm fixed on each column and an arm mounted on each column adapted for oscillation with relation to said fixed arm for engaging the sleeves of a garment.

MAURICE HÉLIOT.
